US0D1073602S

(12) **United States Design Patent** (10) **Patent No.:** **US D1,073,602 S**
(45) **Date of Patent:** **** May 6, 2025**

(54) **DISPLAY STAND**

(71) Applicant: **Apple Inc.**, Cupertino, CA (US)

(72) Inventors: **Jody Akana**, Los Altos Hills, CA (US); **Molly Anderson**, San Francisco, CA (US); **Bartley K. Andre**, Palo Alto, CA (US); **Shota Aoyagi**, San Francisco, CA (US); **Jeremy Bataillou**, San Francisco, CA (US); **M. Evans Hankey**, San Francisco, CA (US); **Richard P. Howarth**, San Francisco, CA (US); **Duncan Robert Kerr**, San Francisco, CA (US); **Peter Russell-Clarke**, San Francisco, CA (US); **Benjamin Andrew Shaffer**, San Jose, CA (US); **Clement Tissandier**, San Francisco, CA (US); **Julian Jaede**, San Francisco, CA (US); **Marine C. Bataille**, San Francisco, CA (US); **Markus Diebel**, San Francisco, CA (US); **Abidur Rahman Chowdhury**, San Francisco, CA (US); **Clara Geneviève Marine Courtaigne**, Palo Alto, CA (US); **Jonathan Gomez Garcia**, San Francisco, CA (US); **Nicolas Pedro Llyk**, Los Gatos, CA (US); **Anthony Michael Ashcroft**, San Francisco, CA (US); **Eugene Antony Whang**, San Francisco, CA (US); **Joe Sung-Ho Tan**, Vienna (AT)

(73) Assignee: **Apple Inc.**, Cupertino, CA (US)

(**) Term: **15 Years**

(21) Appl. No.: **29/929,643**

(22) Filed: **Feb. 23, 2024**

Related U.S. Application Data

(63) Continuation of application No. 29/796,710, filed on Jun. 25, 2021, now Pat. No. Des. 1,016,006.

(57) **CLAIM**

The ornamental design for a display stand as shown and described.

DESCRIPTION

FIG. 1 is a front perspective view of a display stand showing the claimed design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

(Continued)

FIG. 9 is a front perspective view thereof showing the claimed design in an environment in which it may be used; and,

FIG. 10 is a left side view thereof showing the claimed design in an environment in which it may be used.

The broken lines in the figures show portions of the display stand or environment that form no part of the claimed design.

1 Claim, 8 Drawing Sheets
